DESIGN FOR A CLOCK

Clarence R. T. Hess, Prairie View, Ill., assignor to Perfex Corporation, Milwaukee, Wis., a corporation of Wisconsin

Application October 12, 1939, Serial No. 87,636

Term of patent 7 years

To all whom it may concern:

Be it known that I, Clarence R. T. Hess, a citizen of the United States and a resident of Prairie View, in the county of Lake and State of Illinois, have invented a new, original, and ornamental Design for a Clock, of which the following is a specification, reference being had to the accompanying drawing, forming a part thereof.

I claim:

The ornamental design for a clock, substantially as shown.

CLARENCE R. T. HESS.
